LOCKING CAP FOR TANK FILLER SPOUTS

Dawson Friend, Connersville, Ind., assignor to
Stant Manufacturing Company, Inc., Conners-
ville, Ind., a corporation of Indiana

Application April 11, 1951, Serial No. 220,411

8 Claims. (Cl. 70—172)

1

This invention relates to a closure cap for use with a receptacle filler spout and is primarily concerned with the provision of means whereby such a cap can be positively locked to such spout.

My cap is designed primarily for use with a filler spout having the rim of its open end turned outwardly, to provide an axially-facing, annular seating surface, and downwardly, to provide an annular skirt having a plurality of diametrical notches therein, said skirt, between said notches, providing helical cam surfaces axially oppositely facing with respect to said seating surface. Caps designed for use with such a spout have means associated therewith for engaging such cam surfaces to draw the cap axially toward such seating surface upon turning movement thereof relative to said spout. Specifically then my invention relates to means associated with such a cap whereby the cap, after being seated on the seating surface, may be positively locked to the spout against turning movement and removal therefrom.

Ancillary objects will become apparent as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a longitudinal sectional view through a preferred embodiment of my invention shown in association with a filler spout of the type with which it is primarily intended to be used;

Fig. 2 is an inverted perspective view of the cap of Fig. 1, partly broken away and with parts removed for clarity of illustration;

Fig. 3 is a bottom plan view of the cap with parts removed for clarity of illustration;

Fig. 4 is a view similar to Fig. 3 but with additional parts having been added in their proper sequence of assembly; and

Fig. 5 is a plan view of the type of filler spout for which my cap is primarily adapted.

Referring more specifically to the drawings, I have shown a substantially circular cap 10 having a base 11, an annular rim 12 and a lock barrel 13 upstanding near the center thereof on the side coincident with rim 12. Barrel 13 provides an axial socket 14 substantially perpendicular to the cap base 11. A key-controlled cylinder 15 is oscillably mounted in socket 14 and the tumbler pins or discs 16 thereof take into slots (not shown) in the walls of socket 14 to prevent turning of cylinder 15 relative to cap 10 when the key is removed.

The end 17 of cylinder 15 protrudes slightly beyond the end of barrel 13 and has projecting

therefrom a pair of pins 18. Suitable means 19 as shown in Fig. 2 prevents axial removal of the cylinder from socket 14.

A hood shaped element 20 has an end 21 perforated to receive pins 18, said end being seated against cylinder end 17. The skirt 22 of hood 20 surrounds barrel 13 and terminates in a radially outwardly turned flange 23. About a portion of the periphery of said flange, a parabolic spiral cam rim 24 projects therefrom toward cap base 11. Cam rim 24, in my preferred embodiment, extends angularly about the axis of cylinder 15 for slightly less than 180° as shown in Fig. 3.

A pin 25 is carried in base 11. A latch member 26 has one end 27 journaled on pin 25 for oscillation about the axis of said pin in a plane substantially perpendicular to the axis of cylinder 15. Said latch member has upstanding therefrom, at a point remote from pivot pin 25, a locking lug 28 and upturned flanges 29 and 30 defining a channel 31 therebetween. Channel 31 opens outwardly from base 11 and receives the cam rim 24 as clearly shown in Fig. 3.

From an examination of the described structure, it will be seen that oscillation of cylinder 15 within the lock barrel 13, will correspondingly oscillate the associated hood 20 and cam rim 24 to cause latch member 26 to pivot about pin 25, moving the locking lug 28 substantially radially with respect to cap 10.

Projecting from the base 11 in the direction of projection of barrel 13, I provide a plurality of studs 32. A cup-shaped element 33, having a bottom 34 and an annular rim 35, is seated on studs 32 and screws 36 take into threaded bores in studs 32 to hold the cup firmly to base 11.

Cup 33 has a central aperture 37 through which hood 20 protrudes; and the rim of said aperture engages hood flange 23 to hold hood 20 axially immovable but permitting rotation thereof with respect to cup 33 and cap 10. The cup bottom 34 also engages the portion 27 of latch member 26 to confine the same between base 11 and cup bottom 34.

Cup rim 35 has in the periphery thereof a notch 38 which extends radially inwardly into the cup base 34. Thus, locking lug 28 is provided with a substantially radial path for movement into and out of the interior of cup 33, "through" cup rim 35. In its innermost position, locking lug 28 will lie just within the bounds of cup rim 35, as shown in Fig. 4, and in its outermost position, said locking lug will lie just without the bounds of said cup rim.

Cup rim 35 has at diametrically opposite positions a pair of radially inwardly turned toes 39 for a purpose later to become apparent.

My cap as described is designed for use with a filler spout 40 having an axially-facing, annular seating surface 41 and an annular skirt por-

tion 42 spaced outwardly from spout 40. Skirt 42 is interrupted at diametrically opposite points by notches 44, as shown in Fig. 5, said notches extending slightly into the seating surface 41; and is provided with helical cam surfaces 43 on the free edge thereof between notches 44, axially oppositely facing with respect to seating surface 41.

The inner diameter of cup rim 35 is slightly greater than the outer diameter of spout skirt 42. By positioning cap 10 on spout 40 so that toes 39 register with spout notches 44, the toes may be passed through said notches to engage the cam surfaces 43. Rotation of cap 10, when the toes are so positioned, will cause the toes to underride the cam surfaces 43 shifting the cap axially relative to spout 40. Such passage of toes 43 through spout notches 44 may be accomplished, however, only when locking lug 28 is in its outermost position.

Sufficient turning of cap 10 will bring locking lug 28 into registry with one of the notches 44. At this point, rotation of the key-controlled cylinder 15 and its associated hood 20 and cam rim 24 will swing latch member 26 about pivot pin 25, moving locking lug 28 into the interior of cup 33 to enter one of the notches 44. Thus it will be seen that the locking lug 28, so positioned, will prevent such movement of the cap 10 on spout 40 as would return toes 39 to registry with notches 44.

To provide a liquid-tight seal between the cap 10 and the spout seating surface 41, I provide a gasket washer 45 surrounding hood skirt 22 and bearing against the rim of the cup aperture 37. A second gasket washer 46 surrounds hood skirt 22 and is engageable with seating surface 41. A resilient washer 47 is interposed between the gaskets 45 and 46 and at the inner periphery thereof bears against gasket 45 to urge it into sealing engagement with cup aperture rim 37. The outer periphery of washer 47 engages gasket 46 to urge it into sealing engagement with spout seating surface 41 when the cap is in locked position on said spout, as clearly shown in Fig. 1.

A rivet 48 is fixed to hood end 21 and a cupped element 49 is fixed to rivet 48 by means of a "speed nut" 50 or the like. Element 49 acts as a retaining means for gaskets 45 and 46 and washer 47 when the cap is disassembled from the spout 40.

To prevent water and dirt from entering key-controlled cylinder 15, I provide a cover plate 51 hinged to a bracket 52 mounted on cap base 11 and supporting an axle 53. A coiled spring 54 urges cover plate 51 into seating engagement with an annular rib 55 surrounding key-controlled element 15, and a gasket 56 is mounted to said cover plate to bear against rib 55 to insure a tight seal.

I claim as my invention:

1. A device of the class described comprising a base, an element carried for turning movement in said base about an axis substantially perpendicular thereto, a hood carried for turning movement with said element at the end thereof remote from said base and having a skirt, the skirt of said hood surrounding said element and terminating in a parabolic spiral cam rim projecting toward said base, pivot means carried in said base and having an axis eccentric with respect to said element axis, and a latch member journalled on said pivot means and operably connected to said cam rim for oscillation thereby

about said pivot means in a plane substantially parallel to said base.

2. A device of the class described comprising a base, an element carried for turning movement in said base about an axis substantially perpendicular thereto, a member carried for turning movement with said element at the end thereof remote from said base, said member being provided with a cam rim projecting toward said base, pivot means carried in said base and having an axis offset from said element axis, and a latch member journalled on said pivot means and operably connected to said cam rim for oscillation thereby about said pivot means in a plane substantially parallel to said base, said latch member comprising a leaf journalled near one end thereof on said pivot means to lie in a plane substantially parallel to said base and having therein a relatively short channel spaced from said pivot means and a locking lug projecting from said leaf away from said base, said channel receiving said cam rim near the point of tangency of a line through said pivot means tangent to said cam rim.

3. For use with a receptacle filler spout of the type having the rim of its upwardly open end turned radially out to provide an axially-facing, annular seating surface, and down to provide an annular skirt having a plurality of radially-opening, peripherally-spaced notches therein and providing on the edge thereof between said notches helical cam surfaces axially oppositely facing with respect to said seating surface, a closure cap provided with a plurality of peripherally-spaced, radially-turned toes for passage through said notches and retaining engagement with said spout skirt cam surfaces, a lock barrel carried by said cap and supporting a key-controlled element oscillable about the axis of said barrel, a locking lug movably mounted on said cap and movable substantially radially with respect to said cap, and cam means providing an operative connection between said key-controlled element and said locking lug, said lug being enterable in one of said spout notches, in one position of said cap in which said toes engage said skirt cam surfaces, to hold said cap against turning movement relative to said spout.

4. The device of claim 3 in which said cam means comprises a parabolic spiral rim, and a lever pivoted on one end to said cap and having a channel therein receiving said rim, said locking lug being carried on said lever adjacent the opposite end thereof.

5. For use with a receptacle filler spout of the type having the rim of its upwardly open end turned radially out to provide an axially-facing, annular seating surface, and down to provide an annular skirt having a plurality of radially-opening, peripherally-spaced notches therein and providing on the edge thereof between said notches helical cam surfaces axially oppositely facing with respect to said seating surface, a closure cap provided with a plurality of peripherally-spaced, radially-turned toes for retaining engagement with said spout skirt cam surfaces, said cap comprising a base providing a lock barrel, a key-controlled cylinder mounted in said barrel for oscillation about the axis thereof and having a terminal portion near the end of said barrel remote from said base, a hood fixed to said terminal portion having a skirt terminating in a parabolic spiral cam having a rim projecting toward said base, a locking lug pivotally mounted on said base and movable substantially radially

with respect to said base, and means providing an operative connection between said locking lug and said parabolic cam rim, said lug being enterable in one of said spout notches, when said cap is in the position in which said toes engage said spout skirt cam surfaces, to hold said cap against turning movement relative to said spout.

6. For use with a receptacle filler spout of the type having the rim of its upwardly open end turned radially out to provide an axially-facing, annular seating surface, and down to provide an annular skirt having a plurality of radially-opening, peripherally-spaced notches therein and providing on the edge thereof between said notches helical cam surfaces axially oppositely facing with respect to said seating surface, a closure cap provided with a plurality of peripherally-spaced, radially-turned toes for passage through said notches and retaining engagement with said spout skirt cam surfaces, said cap comprising a base providing a lock barrel at the center thereof, a key-controlled cylinder mounted in said barrel for oscillation about the axis thereof and having a terminal portion near the end of said barrel remote from said base, a hood having an end portion fixed to said terminal portion and a skirt terminating in a parabolic spiral cam having a rim projecting toward said base, and a latch member shiftably mounted on said base, said latch member having a locking lug thereon and a channel therein near said locking lug, said parabolic cam rim being received in said channel and said locking lug, upon oscillation of said hood being movable substantially radially with respect to said cap base and enterable in one of said spout notches, when said cap is in the position in which said toes engage said spout skirt cam surfaces, to hold said cap against turning movement relative to said spout.

7. For use with a receptacle filler spout of the type having the rim of the upwardly open end turned radially out to provide an axially-facing, annular seating surface, and down to provide an annular skirt having a pair of radially-opening, diametrical notches therein and providing on the edge thereof between said notches helical cam surfaces axially oppositely facing with respect to said seating surface, a closure cap comprising a base having a lock barrel at the center thereof, a key-controlled cylinder mounted in said barrel for oscillation about the axis thereof and having a terminal portion near the end of said barrel remote from said base, a hood fixed to said terminal portion having a skirt surrounding said barrel and terminating in a radially-outturned flange having, about a portion of its periphery, a parabolic spiral rim projecting toward said base, a pivot pin mounted in said base upon an axis eccentric with respect to said barrel axis, a latch member comprising a leaf having one end thereof mounted for swinging movement about said pivot pin in a plane substantially perpendicular to said barrel axis, a locking lug projecting therefrom near the other end of said leaf substantially perpendicular thereto, said leaf further having a channel near said locking lug opening outwardly from said leaf and receiving said parabolic spiral rim, and an element fixedly supported on said base overlying the radially-outturned flange of said hood to prevent axial movement of said hood away from said base, said element being provided with a pair of diametrical, radially-turned toes on a diameter including said barrel axis, the di-

ameter of a circle concentric with said barrel axis and including the roots of said toes being slightly greater than the diameter of said spout skirt, said toes being registrable with said spout skirt notches and engageable with said spout cam surfaces to move said cap axially toward said seating surface upon turning movement of said cap relative to said spout, said locking lug being enterable in one of said spout notches, after said turning movement of said cap and upon oscillation of the key-controlled cylinder, to hold said cap against turning movement relative to said spout.

8. For use with a receptacle filler spout of the type having the rim of the upwardly open end turned radially out to provide an axially-facing, annular seating surface, and down to provide an annular skirt having a pair of radially-opening, diametrical notches therein and providing on the edge thereof between said notches helical cam surfaces axially oppositely facing with respect to said seating surface, a closure cap comprising a base having a lock barrel at the center thereof, a key-controlled cylinder mounted in said barrel for oscillation about the axis thereof and having a terminal portion near the end of said barrel remote from said base, a pair of pins eccentrically protruding from said terminal portion, a hood comprising an end portion perforated to receive said pins when said end portion is seated against said terminal portion, and a skirt terminating in a radially outwardly turned flange having about a portion of its periphery a parabolic spiral rim projecting toward said base; a pivot pin carried in said base spaced from said hood rim, a latch member mounted for swinging movement about said pivot pin in a plane substantially perpendicular to said barrel axis and having a channel therein opening outwardly from said latch member and said base and receiving said hood rim near the point of tangency of a line through said pivot pin tangent to said hood rim, a locking lug carried by said latch member near said channel for substantially radial movement with respect to said cap; and a cup fixed to said base having an aperture at the center thereof, the rim of which engages said hood flange to prevent axial movement of said hood away from said base, and a peripheral rim projecting therefrom away from said base, said rim having a substantially radial notch therethrough for movement of said locking lug from a position just outside said cup rim to a position just within said cup rim, said rim being of a diameter slightly larger than said spout skirt and providing a pair of diametrical radially-turned toes enterable in said spout notches and engageable thereafter with said spout skirt cam surfaces to move said cap axially toward said spout seating surface upon turning movement of said cap relative to said spout, said locking lug being enterable in one of said spout notches after said turning movement of said cap and upon oscillation of the key-controlled cylinder, to hold said cap against turning movement relative to said spout.
